CLAIM

The ornamental design for a tire tread, as shown and described.

DESCRIPTION

FIG. 1 is a perspective, side elevational view showing my new tire tread design, it being understood that the tread pattern repeats uniformly throughout the circumference of the tire tread, as shown schematically in solid lines.

FIG. 2 is a side elevational view thereof, the opposite side elevational view being identical thereto; and,
FIG. 3 is a fragmentary end elevational view thereof.
